CENTRIFUGE

George L. McCargar, Detroit, Mich.

Application January 20, 1947, Serial No. 723,097

7 Claims. (Cl. 210—74)

1

This invention relates to a centrifugal drier, particularly designed for the substantially continuous handling and drying of leafy vegetables after they have been washed to remove dust, dirt and the like from the leaves. The apparatus used for washing is the subject matter of an application for patent filed of even date herewith Serial No. 723,096, now Patent No. 2,503,556, and the invention of this application is directed to the drier or water-removing apparatus to which the washed leafy vegetables are carried directly after their washing and with water adhering thereto.

It is a primary object and purpose of the invention to provide a novel machine in which leafy vegetables, continuously washed and in a wet condition are rapidly and efficiently dried, with a removal of the water therefrom, so that after drying they may be conveyed to another or other machines for packaging.

An understanding of the invention may be had from the following description, taken in connection with the accompanying drawings, in which,

Fig. 1 is a fragmentary elevation of the centrifugal drying machine of my invention.

Fig. 2 is a plan view thereof.

Fig. 3 is a side elevation from a direction at right angles to the elevation shown in Fig. 1.

Fig. 4 is a central vertical section, somewhat enlarged, through the upper portion of the machine, on the plane of line 4—4 of Fig. 2.

Fig. 5 is a fragmentary central vertical section similar to that shown in Fig. 4 with the parts in a different position.

Fig. 6 is a partial vertical section and side elevation looking at the structure shown in Fig. 4, substantially on the plane of line 6—6 of Fig. 4.

Fig. 7 is a fragmentary enlarged vertical section substantially on the plane of line 7—7 of Fig. 6, and

Fig. 8 is a horizontal section and plan on the plane of line 8—8 of Fig. 3.

Like reference characters refer to like parts in the different figures of the drawings, and the sectional views are taken in the directions indicated by the arrows.

In the structure disclosed, a plurality of vertical supporting posts 1 have connected at their upper ends a horizontal ring 2 of channel cross-section, above which are other spaced vertical posts 3, at their upper ends, a horizontal channel ring 4 being permanently secured. A sheet metal housing having a horizontal bottom 5 located underneath the lower ring 2 and with vertical sides 6 forming a cylindrical wall extends above

2

the horizontal ring 2. At the upper end of the housing, it is continued and bent inwardly and downwardly to make an annular flange 7 at the top of the housing, surrounding a central opening which is bounded by a short vertical annular flange 8, as shown in Fig. 4. At one side of the housing an opening is provided which is closed by a door 9 hinged a short distance above its lower edge at 10 on the lower channel ring member 2, and adapted to swing inwardly and outwardly at its upper portion. In its outer position, the opening in the housing is closed (Fig. 4), the upper edge portions of the door 9 extending immediately within the housing 6. In its inner open position it is tilted inwardly to the position shown in Fig. 5.

A sheet metal cylindrical drum 11, open at its upper end with perforated walls, is positioned at its upper end around the previously mentioned flange 8, and has, preferably, three rods 12 radially spaced from each other (Fig. 2), connected at their outer ends to the drum near its upper end. They extend inwardly and are secured to a collar fixed near the upper end of a vertical shaft 13, which extends downwardly through the drum, through an inverted channel bar 14 secured thereto and at its ends connected to the drum, the shaft 13 extending downwardly to substantially the lower end of the machine, as shown in Fig. 5. Said shaft may be made of a plurality of connected parts all in alignment and in effect, the same as though of a single integral structure.

Two generally semi-circular doors 15 of sheet metal are hingedly connected at opposite sides of the bar 14 and provide a bottom for the drum. The shaft 13 extending downwardly below the bottom of the drum has a bearing in a horizontal inverted channel bar 17, extending diametrically across the upper ring member 4 and secured at its ends thereto, and also through a bearing 18 connected with the bottom 5 of the housing.

The drum 11, at the outer edges of the doors 15 when they are closed, is equipped with two flat metal bars or straps 19, fastened at the inner side 45 of the drum and extending below its lower edges with openings for the passage of retaining or holding pins 20, mounted for longitudinal movement upon brackets 21 (Fig. 7) which are secured at diametrically opposed points at the outer side 50 of the drum 11 and adjacent its lower edges. On each of the brackets 21 a pin actuator 22, of a generally triangular form, as shown in Fig. 7, is pivotally mounted at 23 between its ends, its upper end having a rocking connection with a block on its pin 20, so that when an actuating member 22

is rocked about its pivot 23 in one direction, its associated pin is moved inwardly to pass underneath the outer edge portions of a door 15, as in Fig. 4. When it is moved outwardly, it disconnects from a door permitting it to fall by gravity, as shown in Figs. 5 and 7. A coiled tension spring 24, connected at one end to each actuating member 22, below its pivot 23, and at its upper end to the associated bracket 21, serves to hold the pin actuator 22 in either of the two extreme positions to which it is movable. In the rocking movements of a pin actuator 22 from one extreme position to the other, the line of force of the spring crosses the pivot axis of its pivot 23. At its lower inner and outer corners, each actuating member 22 below its pivot 23, and at its upper projection 22a, the inner projection being in the path of movement of the upper edge of the door 9 when it is moved from its closed outer position in Fig. 4 to its open inner position in Fig. 5, and the outer projection in the path of movement of said door when it is moved back to closing position.

A horizontal shaft 25 is mounted for rocking movement within the housing opposite the door 9. On the shaft a pair of spaced bell crank levers are fixed, one arm 26 of each of which extends substantially to the door 9 and has a roller 27 at its end riding against the inner side of the door. A rod 28 extends across between the free ends of the arms 26, and is located between the inner side of the door and a flat bar 29 (Fig. 4), permanently secured to the door at its lower end and extending upwardly and bent outward so as to be spaced a short distance from the inner side of the door, as shown. Thus when the rock shaft 25 is rocked in a counter-clockwise direction, the door is turned inwardly as in Fig. 5, and when rocked in the opposite direction, is moved to its outer closed position.

The bell crank levers are each completed by a second arm 30 located at an angle to their associated arms 26, and to the upper ends of each of the arms 30, a link 31 is pivotally connected at its lower end, said links at their upper ends having pivotal connections to ears extending downwardly from a horizontal bar 32. From the under side of the bar 32, straps 33 connected thereto extend inwardly toward the transverse frame bar 17 and are hingedly connected thereto by hinges 34 at their inner ends. Two downwardly and outwardly inclined plates 35, of relatively short length, are fastened to the frame bar 17 near its ends, against which the plate 9 engages at its upper edge portions when turned to inner position and which also serve a function in connection with the drop doors 15 at the bottom of the drum 11 to prevent material from passing around the curved edges of a door downwardly into the housing when the door is dropped to lower position.

A platform 36 for the operator of the machine (Figs. 1 and 3) is located approximately midway between its upper and lower ends. Through an endless chain 37 around a sprocket pinion 38, at the outer end of the shaft 25, and a larger sprocket wheel 39 mounted at one side of the housing of the machine and manually movable by means of a hand lever 40 connected to the wheel 39, the door 9 may be alternately swung to its inner and outer positions, shaft 25 being rocked back and forth by moving the lever 40.

The shaft 13 in the operation of the machine is driven continuously at high speed from an electric motor 41 (Figs. 1 and 3), through a belt 42.

Adjacent the lower end of the shaft a brake drum 43 (Fig. 8) is fixed, having around it a brake band 44, adapted to be tightened by actuating a lever 45 (Fig. 1), which is operated by pushing downwardly upon a vertical bar or rod 46 connected at its outer end. The bar 46 extends upwardly through the platform 36 and is equipped with a head 47 to be pressed against by the foot of the operator to brake the speed of movement of the shaft 13 and bring it to rest upon interruption of the electric current going to the motor 41. The switch 48 connected by cable 49 with the motor, for starting and stopping the motor, is mounted at a side of the housing 6 (Fig. 1), so that all of the controls of the machine are conveniently located for access by the operator standing on the platform 36.

The leafy vegetables after their washing are elevated by a conveyor shown at 50, and dumped into a receiving receptacle 51 at the upper end and at one side of the housing, from which they are movable into the rotating perforated drum 11. At a side of the machine in operative lower position with respect to the door 9 and the opening which it closes, a hopper 52 is provided to receive the dried leafy vegetables passing by gravity (Fig. 5) over a dropped door 15 and the inwardly turned door 9 to the hopper, from which they pass to a conveyor 53 which carries them to a packaging machine. The water which is removed through centrifugal action from the vegetables and passes outwardly through the perforations in the walls of the drum 11, is collected above the bottom 5 of the housing and through an outlet opening (Fig. 4) is carried away by a trough 54 (Fig. 1).

In the operation with the parts positioned as in Fig. 4 and with the motor 41 at rest, the drum 11 may be filled with the leafy vegetables and then the motor started. In such position the bottom doors 15 are both latched in their upper closed positions and the vegetables are held from dropping downwardly.

The motor then being started by operating the switch 48, the vegetables are dried through centrifugal action causing the water to be thrown outwardly radially and through the perforations in the walls of the drum 11. After the required time of operation for such centrifugal drying, the switch at 48 is operated to interrupt the current flowing to the motor 41 and the brake is applied to bring the centrifugal drum to a complete stop. After it is stopped, if it is not in the proper position, the operator of the machine may grasp the rods 12 and turn it to position, said rods 12 being so located and one of them given a distinctive color that, as shown in Fig. 2, when moved until it is opposite the operator who stands at the right on the platform in Fig. 2, the drum 11 will be properly located for releasing a door 15. Thereupon the operator grasps the hand lever 40, rocking the shaft 25 counter-clockwise from the position in Fig. 4 to that in Fig. 5.

In such rocking movement the side door 9 is 65 swung inwardly about its hinges 10, as previously described, and in such movement engages the inner lower corner projections 22a on the latch pin actuator 22, which is located in the path of movement of the upper edge of the door, withdrawing the pin which is held in its withdrawn unlatched position through the action of the spring 24 as previously described. The arms 30 of the bell crank levers turning in a counter-clockwise movement, will pass from the position shown in Fig. 4, through the position shown in

dash lines in Fig. 5, to the final position shown in the same figure. During such movement, or at the intermediate position illustrated in dash lines in Fig. 5, the bar 32 comes underneath the bottom of the door 15 of the drum 11 directly above it, lifting it off of its pin 20, which is thus freed for unlatching without any retarding force because of friction. Thereafter, the further continued counter-clockwise movement of the arms 30 moves the bar 32 to its final position in Fig. 5, the unlatched door 15 following it and overlapping, at its lower free edge portions, the upper edge portions of the door 9. The dried leafy vegetables by gravity pass through the opening left at the lower end of the drum 11 by such dropping or lowering of the door 15, and slide down it and the door 9 into the hopper 52.

The operator thereupon reverses the previous movement given to the handle 40, swinging the door 9 to closed position, and during such movement, as shown in Fig. 5, turning the pin actuator 22 by engagement of the door against the outer lower corner projection 22a to move the pin 20 back to holding position, this after the door has been elevated at its outer edges to and above the pin, in the dash line position of bar 32 as shown in Fig. 5. The drum is then turned manually through 180 degrees to bring the other door 15 into the position which had been occupied by the first one, the release and return of which has been described, and the operation is repeated to dump the leafy vegetables from the other side of the drum. After this has been done and said other bottom door 15 returned and latched in its upper position, the cycle is again repeated, with a filling of the drum with the washed vegetables, the rotation of the drum for drying, its stopping, a manual movement to proper position, releasing one of the bottom doors and its return to its latched position, a manual turning of the drum through 180 degrees, and a release and return to latched position of the other bottom door 15.

The construction is very practical and useful and has proved exceptionally satisfactory in service.

The invention is defined in the appended claims and is to be considered comprehensive of all forms of structure coming within their scope.

I claim:

1. In a structure of the class described, a drum open at its upper end having perforated vertical side walls, means for closing the lower end of the drum including a hingedly mounted door, means for rotating the drum about a vertical axis, latching means for holding the door in upper position, a housing around the drum having an opening in the side thereof below the drum, a plate closing said opening hingedly mounted at its lower portion for swinging inward to a downwardly and outwardly inclined position and back to closing position, means operated by the plate for actuating said latching means to move it to released position when said plate is swung inwardly and return it to latching position when the plate is swung to closed position, and manually operable means for swinging said plate from one position to the other, and including a member engageable with the drum closure door and acting to support the door in an elevated position when the latching means therefor is released and the plate is in mid-position.

2. In a structure as described, a vertical shaft, means to drive the shaft, a cylindrical drum having perforated vertical side walls around the up-

per portion of the shaft and connected thereto, two diametrically opposed doors hingedly mounted adjacent their ends at the lower end of the drum, a bar connected to said shaft at opposite sides of which the doors are hingedly mounted, two pins mounted at diametrically opposed positions at the lower end of the drum for inward and outward slideable horizontal movements, said pins extending under the doors at inner positions and beyond their outer edges at outer positions, a movably mounted actuator for each pin, a housing surrounding said drum and spaced outwardly therefrom and extending below the lower end thereof, said housing having an opening at a side thereof, a vertical closure plate for said opening, means hingedly mounting said plate to turn about a horizontal axis at its lower portion, and manually operable means connected with the plate for moving it inwardly and outwardly, said pin actuating means being located in the path of movement of the upper edge of the plate to be turned thereby to withdraw a pin when the plate is moved inwardly and to return said pin to holding position when the plate is moved outwardly, a door at the bottom of the drum being released on such outward withdrawal of its holding pin and dropping to a downwardly and outwardly inclined position in which the door at its lower edges overlaps said plate at its upper edges, each of said doors at the lower end of the drum being releasable upon turning the drum to locate the selected door in a predetermined position with reference to said hinged closure plate.

3. A construction as defined in claim 2, and means connected with and operated by said manually operable means and operated thereby to engage against the under side of a door, the holding pin of which is about to be withdrawn, to slightly elevate the door above said pin during its withdrawal.

4. In a structure of the class described, a support, a housing open at its upper end around the upper portion of said support, a vertical shaft rotatably mounted on the support, a cylindrical drum open at its upper end having perforated vertical walls connected with said shaft and located in the housing near the upper end thereof, an electric motor driving the shaft, two semi-circular doors at the lower end of the drum, a horizontal bar connected with said shaft on opposite sides of which the doors are hingedly mounted, movable holding means, one for each door, mounted on the drum adjacent the outer edges of the doors, a horizontal platform located adjacent the housing below the plane of the lower end of the drum, switch means on the housing above the platform for controlling the starting and stopping of said motor, means mounted below the platform for releasing the door by actuation of its movable holding means when said door is in a predetermined position with respect to the housing, whereby the door may fall by gravity to a downwardly and outwardly inclined position, and manually operable means located above the platform movable in opposite directions and having connection with said door releasing and lowering means, movement in one direction thereof releasing and lowering the door, and in the opposite direction elevating said door and moving its holding means back to holding position with the door in its horizontal position.

5. In a structure of the class described, a drum open at its upper end and having perforated

vertical side walls, means for closing the lower end of the drum including a hingedly-mounted door, means for rotating the drum about a vertical axis, latching means for holding the door in upper closed position, a housing around the drum having an opening in a side thereof below the drum, a plate closing the opening, said plate being movably mounted to move from closing position to a downwardly and outwardly inclined position below the drum and door thereon, in 10 which inclined position the door overlaps the upper edge of the plate, manual means for unlatching said latching means and manual means for moving the plate from one of said positions to the other.

6. The elements of claim 5 in which said manual means for moving the plate also acts to unlatch the latching means on movement of the plate to said inclined position.

7. The elements of claim 6 in which said manual means for moving the plate also acts to close said door on movement of the plate to closing position.
